UNITED STATES PATENT OFFICE.

ABBOTT B. DAVIS, OF SAUGATUCK, MICHIGAN.

TOY BOAT.

1,392,484.

Specification of Letters Patent.

Patented Oct. 4, 1921.

Application filed January 19, 1920. Serial No. 352,427.

To all whom it may concern:

Be it known that I, ABBOTT B. DAVIS, a citizen of the United States of America, residing at Saugatuck, in the county of Allegan and State of Michigan, have invented 5 certain new and useful Improvements in Toy Boats; and I do hereby declare the following to be a full, clear, and exact description of the invention, such as will enable 10 others skilled in the art to which it appertains to make and use the same.

This invention relates to a toy boat, being particularly concerned with the construction of a boat which may be propelled 15 through the water by the mechanical operation of oars connected with the boat with a simulation of the movements made in the manual rowing of boats. It is a primary object and purpose of the present invention 20 to produce a device of this character which effectively attains the ends stated and with a construction very simple in character and which can be manufactured at low cost.

For an understanding of the invention 25 and the construction embodying the same, reference may be had to the following description taken in connection with the accompanying drawing, in which:

Figure 1 is a plan view of the boat, parts 30 being broken away and in section.

Fig. 2 is a longitudinal section through the boat showing the mechanism in side elevation; and

Fig. 3 is a transverse section taken 35 through the boat.

Like reference characters refer to like parts in the different views of the drawing.

The boat has a bottom 1 and sides 2 which may be integrally formed from sheet metal 40 if desired or by the use of any suitable material. A flat metal supporting plate 3 is located across the boat having downturned ends 4 mounted on pintles 5 which extend through the sides 2, whereby said plate may 45 be rocked back and forth about the axis of said pins. A figure 6 is attached to and extends upwardly from the plate 3 being provided with arms 7 which are pivotally mounted at their rear ends and extend from 50 the figure. The ends of oars 8 are attached to the free ends of the arms 7. Said oars pass through suitable openings 9 made in and adjacent the upper edges of the sides 2 of the boat.

55 Directly below the plate 3 a shaft 10 is located being mounted at its ends in the

sides 2 of the boat. This shaft is formed with an off-set portion 11 whereby, on rotation of the shaft, said part 11 acts as a crank and, being disposed between the legs 60 of a U-shaped stirrup 12 attached to the under side of the plate 3, rocks said plate back and forth about the pivots 5, thereby causing the figure 6 to oscillate back and forth as is obvious. This causes a swinging 65 movement of the oars 8 about the points where they pass through the sides of the boat.

A link 13 is connected at its lower end to the off-set portion 11 of the shaft 10 and 70 at its upper end to a cross rod 14 which connects the arms 7. As the shaft 10 is rotated it is apparent that the arms 7 are raised and lowered about their pivotal connection to the figure 6 causing a simultaneous lowering and raising of the outer ends 75 of the oars 8. This motion is timed so that, when the boat is placed in the water, the forward rocking movement given to the figure takes place when the outer ends of the 80 oars 8 are raised to pass above the water, while the backward movement of the figure takes place when the outer ends of the oars are lowered to dip in the water, it being apparent that this simulates a rowing motion 85 and causes the boat to move through the water.

A gear 15 is fixed on the shaft 10 with which a pinion 16 is in engagement, the same being secured at the end of a shaft 17 90 suitably mounted in a frame 18 attached to the bottom of the boat. The end of the shaft 17 is formed with a hook over which a heavy rubber band 19 is placed. This band extends to and is connected with a similarly 95 shaped hook mounted on a shaft 20, the same being suitably mounted at the front end of the boat and passing through a bracket 21 as shown. The free end of the shaft 20 is formed into a crank 23 for turning the same 100 by hand. Adjacent the bracket 21 a ratchet wheel 24 is secured with which a pawl 25 mounted on the bracket 21 may engage to stop movement of the wheel 24 in one direction.

105 It is apparent that the band 19 may be twisted and energy thus stored for driving the shaft 10. When thus driven the figure 6 simulates the movements of the body of one rowing a boat and the oars will alternately dip in and out of the water and cause the boat to move over the water. The con-

struction is relatively simple and may be manufactured at low cost. In practice the same has worked out especially satisfactorily.

5 I claim:

1. In combination, a miniature boat, a supporting plate extending between and pivotally mounted on the sides of the boat, a figure attached to and extending upwardly from said plate, arms pivotally mounted on and extending from the figure, oars pivotally mounted on the boat and connected at their inner ends to the outer ends of said arms, a shaft formed with an intermediate offset portion mounted between the sides of the boat below the supporting plate, a U-shaped stirrup attached to the supporting plate between the sides of which the offset portion of the shaft passes, a link attached 10 to said offset portion of the shaft at one end and to the arms at its opposite end, and means for turning the shaft, substantially 15 as and for the purposes described.

2. In a construction of the character described, a miniature boat, a supporting plate located between and pivotally mounted on the sides of the boat, a figure attached to and extending upwardly from the plate, arms pivotally mounted on and extending from the figure, oars pivotally mounted on the boat one at each side thereof and attached at the inner ends to the outer ends of said arms, a shaft rotatably mounted on and extending between the sides of the boat, means for driving said shaft, means operatively connecting the oars with said shaft, and means operatively connecting the supporting plate with said shaft whereby, on rotation of the shaft, the figure is turned back and forth about the pivotal axis of the supporting plate and the arms are raised up and down about their pivotal connection to the figure, substantially as and for the purposes described.
